LOG BARGE LOADING DEVICE

Filed Sept. 15, 1930

UNITED STATES PATENT OFFICE

JOHN THADDAEUS WILBAND, OF VANCOUVER, BRITISH COLUMBIA, CANADA

LOG BARGE LOADING DEVICE

Application filed September 15, 1930, Serial No. 481,981, and in Canada September 14, 1929.

This invention relates to a log-barge loading device, its object is to facilitate the loading of log barges and in particular of that type of log carrying craft described in the patent application of G. S. Wilband et al. under Serial Number 287,103 and filed June 21, 1928.

The massed assemblage of logs for water transportation whether in the form of rafts of various types or as cargo on specially constructed vessels, has hitherto been a costly and laborious process, frequently involving much wastage of both material and time, and the prime object of my invention is to largely eliminate this. In this connection it is also to be noted that the potential losses to be reckoned with are not only those indicated above but also the fact that with log transportation as commonly practiced the towage cost is inordinately high owing to the unscientific methods of forming the rafts for water transportation. Whereas with the improved log barge above referred to this loss is reduced to probably a one sixth part, and with the loading facilities added as herein described the total economies effected reach a very high value; at the same time the seagoing qualities of the craft are absolutely conserved or improved.

The methods of construction adopted to secure these improvements in efficiency may be broadly stated as follows:

In the log-barge above referred to as elevated central longitudinal shaft is employed, this is suitably supported on columns at a convenient height above the deck of the barge, and extends throughout its entire effective length. I make use of this columnar construction to carry at suitable intervals a short cross beam from which depend on each side of the column hangers carrying a pair of runways, these latter serve to support two trucks on each of which are mounted winding drums with control gear for manual operation on the truck itself, and preferably a self-contained gasoline engine. From each of two hoisting drums on each truck a cable depends in a loop, one end of the cable being secured to the truck on the parbuckle system whereby when a bight of the cable engages a

log only half its weight reacts on the hoist, and by a well-known rolling action the log is readily raised to the required level.

Thus far the operative gear indicated provides merely for raising logs and traversing them to any desired position for trimming purposes, and to facilitate the trimming operation the deck of the barge is provided with transverse beams suitably spaced longitudinally and so positioned that their upper surface presents a declination from the central row of columns to the side edge of the barge, and thus provides an efficient skidway for easily trimming the logs when deposited thereon by the manipulation of the hoisting gear.

But to make this equipment fully effective for the purposes in view I employ in conjunction with it a further feature which is a salient part of the invention. In order to make the hoisting equipment absolutely effective the logs are brought immediately below the hoisting drums. To effect this a loading-passage or water-way is built into the hull of the barge, this takes the form of a deep comparatively narrow parallel recess cut through the deck and extending down to below water level. This loading-passage is central and longitudinal of the barge and extends inwardly and right-angularly from the stern end of the barge, thus bifurcating the stern of the craft vertically. It is obvious that this water-way or loading-passage provides a means of floating the logs immediately under the hoisting drums traversing the runways and that they may be readily raised without loss of time or motion.

It is to be noted that the vertical supports for the runways above the water way are slightly modified at this part. A narrow arch preferably of steel framework spanning the loading passage, and supporting from its top inner side the runways which pass through it. The invention is more clearly described by the aid of the accompanying drawing which forms a part of this application, and in which

Fig. 1 is a plan of the log-barge showing the transverse skidways, and the longitudinal central runways, with the loading-passage

at the stern, covered by the narrow arch.

Fig. 2 is a longitudinal section on line 2—2 of Fig. 1.

Fig. 3 is a cross section on line 3—3 of Fig. 5 2 to an enlarged scale.

In the drawing the numeral 6 indicates the deck of a barge, which in this case is built with a pronounced declination from the centre to the sides of the craft. Transversely positioned above the deck 6 cross beams forming the surface of the skidway which facilitates the loading of the logs are shown at 7. The stern portion 8 is bifurcated in Fig. 1 by the recessed water-way 9, this being spanned 10 from the deck 6 by the narrow arch or tunnel structure 10, which latter may be of open steel work if preferred. The hinged stanchions 11 and the chain or cable 12 which is wound on the shaft 13 concern the unloading 15 feature and are no part of the present invention. The vertical members 14 serve as columns to support the shaft 13 and the cross beams 15 from which depend the hangers 16 carrying the runways 17.

20 Traversable on each pair of the runways are the trucks 18, each of which carry a pair of cable drums 19, for hoisting the logs with the cable 21, one end of the latter being secured to the drum and one end to the truck, 25 on the parbuckle system. Fig. 3 shows the logs already loaded at 22, one log in the water at 23 and another at 24 being raised, the water level is indicated at 25, the keel or bottom at 26, the bow at 27, and the stern at 8.

30 From the description it will readily be noted that logs may be floated endwise into the loading-passage or recessed water-way 9 so that they may engage the two looped cables 21 and be quickly raised to the level of the 35 deck or load as the case may be, and thence traversed longitudinally until clear of the tunnel structure 10, when they are free to be disposed transversely by suitable means at any desired point necessitated by the trim of 40 the load.

To facilitate the maneuvering of the barge, buoyance tanks 28 may be built into the hull, to more satisfactorily obtain the required listing effect.

45 Having now fully described the nature of my said invention, I declare that what I claim and desire to secure by Letters Patent, is:

50 1. A loading device for a log-bar^{ge} comprising in combination, a central longitudinal water-way formed in the said barge and being of the nature of a deep recess cut through the deck and hull projecting inwardly and right-angularly from the stern end of 55 the said barge and having substantially vertical parallel sides whereby logs may be floated into said water-way from the stern of the craft and made conveniently available for direct vertical elevation to any desired level, 60 a series of vertical supports of the nature of 65

columns in spaced apart relation and positioned longitudinally and centrally of said barge, said series extending from the inner end of said water-way recess to the end of the effective loading space of said barge, an elongated inverted U-shaped vertical support of the nature of a narrow arch or tunnel spanning the said central recess, a runway on each side of and supported from said columns, 70 said runway passing through and supported from the inner side of said narrow-arch, a traversable truck on each said runway, said truck being provided with hoisting actuating and controlling means, whereby logs floating within said water-way or loading-passage 75 may be directly raised to any desired level and traversed longitudinally to any position necessary for the correct trimming of the load.

2. A loading device for a log-bar^{ge} comprising in combination with the said barge a series of columns positioned longitudinally and centrally of said barge, a series of transverse beams secured across the deck of said barge and forming a transverse skidway 80 thereupon, said skidway being suitably declined from the longitudinal centre line of said barge to the sides thereof, a runway on each side of and supported from said columns, a traversable truck on each said runway, said 85 truck being provided with means for hoisting logs and means for actuating and controlling said hoisting means, whereby logs may be floated endwise and in alignment with said columns and raised by said hoisting 90 means and traversed longitudinally to any desired position on said barge.

In testimony whereof I have hereunto affixed my signature.
